(57) **CLAIM**

The ornamental design for a cart probe holder with tray as shown and described.

DESCRIPTION

FIG. 1 is a top-front-left perspective view of a cart probe holder with tray according to the claimed design.

FIG. 2 is a front view of the cart probe holder with tray.

FIG. 3 is a rear view of the cart probe holder with tray.

FIG. 4 is a right side view of the cart probe holder with tray.

FIG. 5 is a left side view of the cart probe holder with tray.

FIG. 6 is a top view of the cart probe holder with tray.

FIG. 7 is a bottom view of the cart probe holder with tray.

FIG. 8 is an enlarged partial bottom-right perspective view of the cart probe holder with tray; and,

FIG. 9 is an enlarged partial top-left perspective view of the cart probe holder with tray.

The dash-dash broken lines in the drawings depict portions of the cart probe holder with tray that forms no part of the claimed design. The dash-dot-dot broken lines in FIGS. 8 and 9 depict the bounds of the enlarged views and form no part of the claimed design.

1 Claim, 9 Drawing Sheets
